UNITED STATES PATENT OFFICE.

ARCHIBALD McROBERT BLAIN, OF DEERFIELD, VIRGINIA.

PITMAN-CONNECTION.

SPECIFICATION forming part of Letters Patent No. 339,733, dated April 13, 1886.

Application filed January 27, 1885. Renewed September 23, 1885. Serial No. 177,912. (No model.)

To all whom it may concern:

Be it known that I, ARCHIBALD McROBERT BLAIN, of Deerfield, in the county of Augusta and State of Virginia, have invented certain new and useful Improvements in Pitman-Connections; and I do hereby declare that the following is a full, clear, and exact description of the invention, which will enable others skilled in the art to which it appertains to make and use the same, reference being had to the accompanying drawings, which form a part of this specification, and in which—

Figure 1 is a plan view of my improved pitman - connection for harvesters and other machinery. Fig. 2 is a horizontal longitudinal sectional view of the same. Fig. 3 is a transverse vertical sectional view taken on the line $x-x$ in Fig. 2, and Fig. 4 is a detail view illustrating the parts composing my improved pitman-connection detached from each other.

The same letters refer to the same parts in all the figures.

This invention relates to pitman-connections for harvesters and other machinery; and it has for its object to provide a device which shall possess superior advantages in point of simplicity, durability, and general efficiency, and in which the cutting of a screw-thread in the end of the pitman is obviated, while at the same time provision is made for the lengthening and shortening of the same, and for its turning in its bearings, so as to accommodate itself to the tilting of the sickle when the device is applied to a harvester.

With these ends in view the invention consists in the improved construction and arrangement of parts, which will be hereinafter fully described, and particularly pointed out in the claims.

In the drawings hereto annexed, A designates a tubular sleeve or bearing adapted to be journaled upon the wrist-pin B of a disk or crank, C, by means of which the pitman is to be operated, and having a laterally-extending socket, D, which is interiorly screw-threaded, so as to receive a tubular screw-threaded plug, E, the outer end of which is provided with a wrench-seat, F, to receive the key or wrench by means of which it may be manipulated. Journaled in the plug E is the

pitman-rod G, the inner end of which has a collar or shoulder, H, to prevent its displacement, and the outer end of which has a lateral pin or stud, I, to form the connection with the sickle-bar or other part to be operated.

55

It will be seen that the pitman-rod is capable of turning freely in its tubular plug or bearing, which latter may be adjusted so as to adjust the length of the pitman-rod. When the plug E is screwed out, washers J are to be placed under the shoulder of the wrench-seat and in the bottom of the socket D.

From the foregoing description, taken in connection with the drawings hereto annexed, the operation and advantages of this invention will be readily understood. It is simple, inexpensive, convenient, and possessed of great strength and ease of adjustment.

Having thus described my invention, I claim and desire to secure by Letters Patent of the United States—

1. In a pitman-connection, the combination of a socket, a tubular plug adjustable in the same, and a pitman-rod journaled in the said plug, substantially as and for the purpose set forth.

2. In a pitman-connection, the combination of a socket mounted laterally upon an eye or journal, a tubular plug adjustable in the said socket, and a pitman-rod journaled in the said plug, and having a shoulder at its inner end, substantially as and for the purpose herein set forth.

3. In a pitman-connection, the combination of an interiorly-screw-threaded socket having an eye or journal, a tubular plug adjustable in the said socket, and having a wrench-seat at its outer end, a pitman - rod journaled in the said tubular plug, and having a shoulder at its inner end, and adjusting - washers arranged below the collar of the wrench-seat and at the bottom of the socket, substantially as and for the purpose herein set forth.

In testimony that I claim the foregoing as my own I have hereunto affixed my signature in presence of two witnesses.

ARCHIBALD McROBERT BLAIN.
